(57) CLAIM

The ornamental design for a shoe, as shown and described.

DESCRIPTION

FIG. 1 is a side view of a shoe showing my new design; FIG. 2 is a front perspective view thereof; and, FIG. 3 is a front view thereof.

The broken line immediately adjacent to the front of the shaded area defines the bound of the claimed design and forms no part thereof. The broken lines depicting the remainder of the shoe form no part of the claimed design.
